US00D620510S

(12) **United States Design Patent**
Hall(10) **Patent No.:** US D620,510 S
(45) **Date of Patent:** ** Jul. 27, 2010(54) **DRILL BIT**(75) Inventor: **David R. Hall**, Provo, UT (US)(73) Assignee: **Schlumberger Technology Corporation**, Houston, TX (US)(**) Term: **14 Years**(21) Appl. No.: **29/304,177**(22) Filed: **Feb. 26, 2008****Related U.S. Application Data**

(63) Continuation-in-part of application No. 11/837,321, filed on Aug. 10, 2007, now Pat. No. 7,559,379, which is a continuation-in-part of application No. 11/750,700, filed on May 18, 2007, now Pat. No. 7,549,489, which is a continuation-in-part of application No. 11/737,034, filed on Apr. 18, 2007, now Pat. No. 7,503,405, which is a continuation-in-part of application No. 11/686,638, filed on Mar. 15, 2007, now Pat. No. 7,424,922, which is a continuation-in-part of application No. 11/680,997, filed on Mar. 1, 2007, now Pat. No. 7,419,016, which is a continuation-in-part of application No. 11/673,872, filed on Feb. 12, 2007, now Pat. No. 7,484,576, which is a continuation-in-part of application No. 11/611,310, filed on Dec. 15, 2006, now Pat. No. 7,600,586, application No. 29/304,144, which is a continuation-in-part of application No. 11/278,935, filed on Apr. 6, 2006, now Pat. No. 7,426,968, which is a continuation-in-part of application No. 11/277,294, filed on Mar. 23, 2006.

Primary Examiner—Sandra Snapp*Assistant Examiner*—Patricia Palasik(74) *Attorney, Agent, or Firm*—Holme Roberts & Owens LLP(57) **CLAIM**

The ornamental design for a drill bit, as shown and described.

DESCRIPTION

FIG. 1 is a bottom perspective view of the drill bit.

FIG. 2 is a side view of the drill bit with an enlarged detail; and,

FIG. 3 is a perspective view of the drill bit.

The broken line showing of the drill bit is included for the purpose of illustrating portions of the drill bit and forms no part of the claimed invention.
